[57] CLAIM

The ornamental design for an automobile grill, as shown and described.

DESCRIPTION

FIG. 1 is a front elevational view of an automobile grill showing my new design;

FIG. 2 is a top plan view thereof;

FIG. 3 is a bottom plan view thereof; and,

FIG. 4 is a left side elevational view thereof, the right side being a mirror image.

A grill emblem shown in dotted line, and the rear of the automobile grill form no part of the claimed design.
